CLAIM

The ornamental design of a base housing for a multi-feature telephone call processor, as shown and described.

DESCRIPTION

FIG. 1 is a perspective view of a base housing for a multi-feature telephone call processor, showing our new design;

FIG. 2 is a top plan view thereof;

FIG. 3 is a front elevation thereof;

FIG. 4 is a rear elevation thereof;

FIG. 5 is a side elevation thereof, the opposite side being a mirror image of the side shown; and,

FIG. 6 is a bottom plan view thereof.

The broken line disclosure of a telephone handset and cord are for illustrative purposes only and forms no part of the claimed design.
